UNITED STATES PATENT OFFICE.

JAMES EDWARD SMOOT, OF CONCORD, NORTH CAROLINA.

FIRE-ESCAPE.

SPECIFICATION forming part of Letters Patent No. 595,082, dated December 7, 1897.

Application filed May 14, 1896. Serial No. 591,533. (No model.)

To all whom it may concern:

Be it known that I, JAMES EDWARD SMOOT, a citizen of the United States, residing at Concord, in the county of Cabarrus and State 5 of North Carolina, have invented a new and useful Fire-Escape, of which the following is a specification.

This invention relates to fire-escapes; and the object in view is to provide a device of 10 this character which may be used upon the exterior wall of any building and which is especially designed for use upon a projecting balcony located beneath an elevated window of the building.

15 The improved fire-escape embodies a flexible ladder, a windlass upon which the ladder is adapted to be wound and from which it may be readily unwound when required, a hinged casing for inclosing the windlass and 20 ladder and protecting the same from the weather and also giving an ornamental finish to the balcony, and also embodies suitable mechanism for winding and unwinding the ladder, said mechanism being so arranged as 25 to be capable of being operated by a person standing in a safe position upon the balcony or inside of the window, as may be desired.

A further object of the invention is to so combine and arrange the features above enumerated as to facilitate the act of getting 30 from the balcony upon the ladder, or vice versa, and to remove as far as possible the element of danger.

With the above objects in view the invention 35 consists in an improved fire-escape embodying certain novel features and details of construction and arrangement of parts, as hereinafter fully described, illustrated in the drawings, and pointed out in the claim.

40 In the accompanying drawings, Figure 1 is a perspective view showing the preferred application of the improved fire-escape to a building, the latter being provided with an elevated projecting balcony and with projecting platforms adjacent to windows located 45 under the balcony. Fig. 2 is a vertical sectional view of the same. Fig. 3 is a detail perspective view of the folding crank-handle for operating the windlass.

50 Similar numerals of reference designate

corresponding parts in the several figures of the drawings.

Referring to the accompanying drawings, 1 designates an elevated balcony projecting from the exterior wall of a building and located, preferably, at one of the uppermost windows. This balcony comprises a substantially horizontal platform, upon which one or more persons may stand, said platform being supported upon suitable consoles and provided at each side with a balustrade 2. The bottom sills 3 of the balustrades are extended beyond the normal front of the balcony to support side brackets 4, of any desired ornamental form, said brackets also serving as supports for a windlass 5.

The windlass 5 comprises a horizontal shaft which is journaled at its opposite ends in the brackets 4 and provided at or near each end with flanges 6. At one end and upon the outside of the adjacent flange 6 a spur gear-wheel 7 is mounted fast upon the windlass-shaft, and this gear meshes with an intermediate gear journaled upon one of the balustrades, which intermediate gear (indicated at 8) 75 meshes with another gear 9, also journaled conveniently on the balustrade and arranged inside of a gate 10, forming a safety-guard for the front end of the balcony.

11 designates a crank-handle, the inner end 80 of which is bifurcated or forked, and the ends of the fork are connected pivotally to the inner gear-wheel 9 by means of one or more eyes or staples 12. This construction permits the handle to be folded flatwise against 85 the gear-wheel 9 when not required for use, and at the same time permits the handle to be swung outward perpendicularly to the face of the gear-wheel when it is desired to turn said wheel for winding or unwinding 90 the windlass 5.

13 represents a housing, preferably of sheet metal, which extends around the peripheries of the several gear-wheels and protects them from the weather and also obviates the liability of a person's clothing being caught between the teeth of the wheels while in operation. The handle 11 when it is folded is arranged within the housing 13.

The gate 10, above referred to, is swung be- 100

tween suitable posts 14, being hinged to one of said posts and provided at its swinging end with a catch or latch 15 for engaging the opposite post, thus enabling the gate to be 5 readily opened or held closed.

Upon the windlass 5 is wound a flexible ladder 16. This ladder is composed of parallel chains or wire cables 17, which are connected at suitable intervals by cross rods or 10 bars 18, forming the rungs of the ladder. The ladder is of sufficient length to reach from the balcony to the ground and is attached at its upper end to the windlass-shaft, being adapted to be wound upon the windlass and 15 within the plane of the peripheries of the end flanges 6. At the front ends of the sills 3 is located a horizontal cross-bar 19, which may be either in the form of a stationary bar or it may be provided with a roller extending 20 the entire length thereof. In the winding and unwinding of the ladder this bar or roller 19 serves as a guide over which the ladder runs, serving also to hold the ladder offset from the windlass, and said rod or roller also serves as 25 a convenient handhold for a person in ascending or descending.

20 represents a casing of sheet metal or other suitable material having a curved front wall 21, which overlies and covers the windlass 30 and ladder when not in use, and which also comprises a horizontal bottom wall which underlies the windlass, &c., and conceals the same from view from beneath the balcony. This horizontal base portion extends under 35 the sills 3 and is hinged at its inner edge underneath the sills, as shown at 23, whereby the casing is adapted to swing downward for uncovering the windlass, &c. From the inner or hinged edge of the casing a plate or 40 flooring 24 extends inward to the normal front edge of the balcony-platform, thereby entirely concealing the windlass, &c., from persons passing beneath the balcony.

25 indicates a chain or its equivalent, which 45 is attached at one end to one corner of the casing 20, the other end being attached to the balustrade or other convenient point. By means of this chain the casing 20 may be raised or lowered when required.

50 At the windows located beneath the balcony are arranged projecting platforms 26, which extend outward into proximal relation to the depending ladder, thus enabling persons in other stories of the building to get 55 access to the ladder, which, by the construction above described, hangs at a considerable distance from the wall of the building.

By means of the construction above described the flexible ladder when not in use 60 is drawn up out of the way of persons on the ground and is entirely concealed from view.

When in use, the ladder hangs at a considerable distance from the burning building, thus to a great extent protecting persons ascending or descending the ladder from the flames, 65 smoke, and heat. If desired, however, the ladder may be arranged close to the wall and the operating mechanism arranged to be operated from the interior of the building, in which case the balcony and platforms at the 70 lower windows may be dispensed with. Instead of the platforms at the lower windows poles with hooks at their ends may be used for drawing the suspended ladder inward, thus giving persons on the lower floors access 75 to the ladder.

The various parts of the apparatus may be constructed in very light or skeleton form, so as to reduce their weight and give them an ornamental appearance. 80

The sill 27, under the gate 10, is coved in its inner face, as shown at 28, so as to form a bead 29 at its upper edge, said bead providing a handhold for persons while getting on and off the ladder. 85

When the ladder is lowered in operative position, it enables the firemen to ascend to any floor of a burning building for the purpose of fighting the flames and rescuing persons. 90

The fire-escape is very simple in construction, may be manufactured at low cost, and is perfectly practicable and reliable and may be made ornamental to the building upon which it is placed. 95

It will be understood that the apparatus is susceptible of various changes in the form, proportion, and minor details of construction which may accordingly be resorted to without departing from the spirit or sacrificing 100 any of the advantages of this invention.

Having thus described the invention, what is claimed as new is—

The combination with an elevated balcony, having a balustrade, of a windlass journaled 105 in the projecting end of the balcony outside of the balustrade, a flexible ladder adapted to be wound upon the windlass, suitable gearing for operating the windlass, a hinged casing adapted to cover the windlass and ladder 110 and to conceal the same, and a flexible connection attached at one end to said casing and having its opposite end arranged within reach of a person standing on the balcony, substantially as described. 115

In testimony that I claim the foregoing as my own I have hereto affixed my signature in the presence of two witnesses.

JAMES EDWARD SMOOT.
